W. H. BLAKE

HAIRBRUSH

Filed Dec. 8, 1927

Inventor
William H. Blake

By Horatio E. Bellows

Attorney

UNITED STATES PATENT OFFICE.

WILLIAM H. BLAKE, OF ATTLEBORO, MASSACHUSETTS, ASSIGNOR TO JAMES E. BLAKE CO., OF ATTLEBORO, MASSACHUSETTS, A CORPORATION OF MASSACHUSETTS.

HAIRBRUSH.

Application filed December 8, 1927. Serial No. 238,549.

My invention relates to a combined comb and hair brush, it being understood that by the term hair brush is intended either a brush which includes a projecting handle or a brush commonly styled a military brush.

The essential objects of my invention are to provide a structure wherein the comb may be substantially housed in the brush; to enable the comb to be readily removed therefrom; to render the combination compact; and to attain these ends in a simple and inexpensive manner.

To the above ends essentially my invention consists in such parts and in such combinations of parts as fall within the scope of the appended claims.

In the accompanying drawings which form a part of this specification

Figure 1 is a plan view of a brush embodying my invention.

Figure 2, a section of the same on line 2—2 of Figure 1, and

Figures 3 and 4, sections taken on line 3—3 of Figure 2, and 4—4 of Figure 1, respectively.

Like reference characters indicate like parts throughout the views.

As herein shown my brush consists of a back represented generally by the reference numeral 8, comprising in this instance a body portion 9 and a handle portion 10. The top and side of the body is encased in a metal shell 13, and a hollow tubular extension upon the end of the body with a closed end constitutes the handle portion 10 of the back. The shell embraces the filler block 15 provided with a longitudinally disposed hole 16 extending, in this case, entirely through the block. The hole is preferably broad and shallow. Abutting against the lower face of the block 15 is an auxiliary block 17 held tightly in place by an annular

bead or flange 18 upon the bottom of the shell 13. Fixed as usual in holes 20 in the block 17 are tufts of bristles 21.

A flat comb 23 is slidably fitted in the hole 16 and is held in any desired position therein by friction. The length of the comb is slightly greater than the length of the brush back. One end, therefore, abuts against the end of the handle 10, while the other end projects slightly beyond the end of the back, as shown in Figure 2. This is the normal position of the comb. In this position a minimum of space is occupied by the combined parts and the projecting portion of the comb affords a ready means for grasping and drawing the latter out of engagement with the brush. In Figure 3 the comb is shown partially withdrawn.

I claim:—

1. In a hair brush, a shell, a flange upon the shell, a filler block in the shell provided with a longitudinal hole, a second block in the shell embraced by the flange and engaging the filler block, bristles in the second block, and a comb slidably mounted in the hole and engageable at one end with the shell.

2. In a hair brush, a shell comprising a body portion and a tubular extension having a closed end, a filler block in the shell, a second block in the shell abutting against the filler block, a flange on the shell engaging the second block, said filler block being provided with a longitudinal hole extending throughout its length in alignment with the extension, and a comb detachably mounted in the hole and extending the length of the tube and projecting exterior of the shell.

In testimony whereof I have affixed my signature.

WILLIAM H. BLAKE.
